Primary Examiner — Mary Ann Calabrese*(74) Attorney, Agent, or Firm* — Bryan Cave LLP(57) **CLAIM**

The ornamental design for pair of advertising panels affixed to the entry portion of a shopping cart corral, as shown and described.

DESCRIPTION

FIG. 1 is a perspective view of the pair of advertising panels affixed to the entry portion of a shopping cart corral;

FIG. 2 is a right side view thereof;

FIG. 3 is a left side view thereof;

FIG. 4 is a front view thereof;

FIG. 5 is a rear view thereof; and,

FIG. 6 is a top view thereof.

The broken line showings of the shopping cart corral in FIGS. 1-6 are for the purpose of illustrating an environment only and form no part of the claimed design.
